UNITED STATES PATENT OFFICE.

WILLIAM HUNTER, OF SAN FRANCISCO, CALIFORNIA.

DRAFT-REGULATOR.

SPECIFICATION forming part of Letters Patent No. 321,502, dated July 7, 1885.

Application filed October 31, 1884. (No model.)

To all whom it may concern:

Be it known that I, WILLIAM HUNTER, of the city and county of San Francisco, State of California, have invented an Improvement 5 in a Draft-Regulator; and I hereby declare the following to be a full, clear, and exact description of the same.

My invention relates to a draft-regulating device which is especially useful in fire-places 10 and grates, but may also be used in other places where fuel is to be consumed and it is desirable to control the draft and direct the heat into the room or into the proper channel, or to prevent it from too rapid exhaustion.

It consists of a back or top plate having slots or perforations with movable slides or dampers by which the openings are controlled.

Referring to the accompanying drawings 20 for a more complete explanation of my invention, Figure 1 is a front view of the grate, showing the application of my device. Fig. 2 is a section of the same.

In Figs. 1 and 2 I have shown my invention 25 as applied to the grate or fire-place in which A is the front of the basket; B, the back wall with the grate-bars in the usual position at the bottom, as shown at C.

My invention consists of a plate, D, having 30 a number of vertical longitudinal slots, E, made in it and openings flaring or diverging toward the front from these slots, the plate being of considerable thickness, so that the slots are made through the rear portion.

This plate is preferably set at an angle from 35 the rear portion of the fire-place, while its upper edge rests against the top front portion, so that when the openings E are closed

40 there will be no access to the chimney. The sliding plate F is fitted to move transversely across the back of the plate D, and this sliding plate has slots G of different widths, or with offsets between top and bottom made in it, so that when it stands in one position

45 it may entirely close the slotted openings E, and when moved back it may open the whole or any desired portion of the upper part of the slots. When the fire is first made, this

50 plate will be moved so that all the slots E will be open, and a complete draft through the grate and up the chimney will be established until the fuel is in thorough combustion, when this sliding plate F may be moved 55 so as to cut off one-quarter, one-half, or two-

thirds or more of the draft, as may be desired; and when the fuel is burned to such a point that there is comparatively little smoke, the slide may be moved so as to cut off all but very small opening at the top, through 60 which any small amount of smoke or gases may escape. The action of this device is to throw the heat outward into the room, to prevent a strong draft which carries the great portion of the heated air up the chimney, 65 and more particularly to provide a certain circulation within the room, whereby sufficient air is supplied to the bottom of the grate from the lower part of the room to promote the combustion, while the heat is thrown 70 outward from the deflecting-plate D and rises to the upper part of the room. In becoming cold this air will sink to the lower part, to be again turned into the grate, and thus a circulation will be established between the room 75 and the grate by which the air of the room will be kept warm for a much longer period than when the chimney-connection is left open. The small opening left in the exterior upper portion of this device will be sufficient 80 to allow the escape of any small quantity of unconsumed carbon and gases, which may be detrimental if allowed to escape into the room. By the use of this plate I am enabled to correct in a great measure the defect caused 85 by gusts of wind blowing down the chimney, which causes the grate to smoke very badly. A projection or knob extending forward from the sliding plate D provides a suitable means for moving it to open or close the spaces. 90

Having thus described my invention, what I claim as new, and desire to secure by Letters Patent, is—

In a fire place or grate, the inclined plate fixed above and behind the fire, within the 95 chimney or flue opening, and having the vertical slots, as shown, in combination with a secondary plate sliding transversely between guides upon the back of the first plate, and having slots made of different widths or with 100 offsets between the top and bottom, said slots aligning themselves with those in the first plate, whereby the position of the draft-opening may be regulated, substantially as herein described.

In witness I have hereunto set my hand.

WILLIAM HUNTER.
